(57) **CLAIM**

The ornamental design for an illuminated loudspeaker as
shown and described.

DESCRIPTION

FIG. 1 is a front view of a first embodiment of an illuminated
loudspeaker, showing the new design;

FIG. 2 is a front view of a second embodiment of the
illuminated loudspeaker, showing the new design;

FIG. 3 is a front view of a third embodiment of the
illuminated loudspeaker, showing the new design; and,

FIG. 4 is a front view of a fourth embodiment of the
illuminated loudspeaker, showing the new design.

The evenly spaced broken lines illustrate portions of the
design that form no part of the claimed design. The dash-dot
broken lines represent the boundaries of the claimed design
and form no part of the claimed design. The brighter
arc-shaped areas enclosed in broken lines represent illumi-
nated portions of the loudspeaker face that form no part of
the claimed design. The remaining brighter arc-shaped areas
represent illuminated portions of the loudspeaker face that
form part of the claimed design.
